UNITED STATES PATENT OFFICE

FRANKLIN S. HOGG, OF NEW YORK, N. Y.

DISPENSING NOZZLE

Application filed June 9, 1931. Serial No. 543,196.

This invention relates to dispensing devices, and has particular reference to a nozzle which is especially designed to be associated with a sealed container, for facilitating the pouring of liquids therefrom.

The invention broadly aims to provide an improved dispensing nozzle which is so fashioned as to afford means for simultaneously forming dispensing and venting openings in a sealed container while establishing a fluid tight connection between the nozzle and the walls of the openings thus formed, whereby to permit the contents of the container to be poured therefrom in a solid stream with a high degree of accuracy in order to avoid spillage and wasting of the contents.

The invention further comprehends a device of the character set forth which includes resilient means for retaining the same in associated relation with a container.

The invention furthermore contemplates a dispensing device of the indicated character which is extremely simple in its construction and mode of use, which is inexpensive to produce and which is highly efficient in its purpose.

With the above recited and other objects in view, reference is had to the following description and accompanying drawings, in which there is exhibited one example or embodiment of the invention, while the claims define the actual scope of the same.

In the drawings:

Figure 1 is a partial side and sectional view of a container with the dispensing device emplaced thereon and shown in section.

Figure 2 is a perspective view of the dispensing device removed.

Referring to the drawings by characters of reference, A designates a container having an upper end wall B and formed with the usual peripheral bead C. The dispensing device includes a base 5, preferably constructed of resilient sheet metal provided at its outer end with a depending spring clip 6 and formed intermediate its ends with longitudinally spaced openings 7 and 8. A tubular pouring spout 9 is carried by and extends through the opening 7 of the base and may be soldered or otherwise secured in place.

The pouring spout 9 has an upper portion 10 extending above the base 5 and provided with a closed headed upper end 11. The portion 10 between the head and the base is provided with a lateral or outwardly projecting, downwardly curved outlet nozzle 12 which extends beyond the outer end edges provided with a clip 6. The spout 9 has an inner or depending portion 13 which is preferably tapered or of gradually decreasing diameters downwardly and is cut off at an angle at its open lower end to provide a perforating pointed terminal 14 which is designed to be initially driven through the container top B for avoiding the dispensing opening therein.

In order to provide means for avoiding a venting opening, a tubular, preferably downwardly tapering perforating element 15 extends through the opening 8, and said element is also cut off at an angle to provide a pointed entering terminal 16 which is designed to be driven through the container top B to form a vent opening therein.

In use, the terminal 14 is driven or forced into the container top B at a point spaced from the outer periphery so that the spring clip 6 will snap over behind the peripheral bead C, and the perforating element 15 is also forced through the top B so that the base 5 overlies said top in the manner illustrated. When this has been accomplished, the device will be operatively associated with the container A to facilitate the pouring and dispensing of the contents therefrom, it being understood that the element 15 functions to vent the container and permit of the pouring of the contents in a solid stream. Due to the tapering of the portion 13 and the element 15, an intimate sealing engagement between the walls of the opening in the top and the outer periphery of the portion 13 and element 15 will obtain to prevent leakage. The spring clip 6 will serve to prevent accidental displacement of the device from the container while the portion 10 above the outlet nozzle 12 will afford a space to increase the head of liquid while flowing from the container during the pouring operation.

From the foregoing, it will thus be seen

that a simple and efficient means has been provided for facilitating the dispensing of liquid contents from sealed containers.

While there has been illustrated and described a preferred embodiment of the invention, no limitation is necessarily intended to the precise structural details, and variations and modifications which properly fall within the scope of the claims are reserved.

What is claimed is:

1. A device attachable to a sealed container for facilitating the pouring of the contents thereof, said device including a base having a spring clip at one end thereof, a tubular pouring spout carried by and extending through the base, said spout having a closed headed outer end and an outwardly and laterally projecting outlet nozzle between said base and said outer end, said spout being formed with an open inner end having a tapered container perforating terminal.
2. A device attachable to a sealed container for facilitating the pouring of the contents thereof, said device including a base having a spring clip at one end thereof, a tubular pouring spout carried by and extending through the base, said spout having a closed headed outer end and an outwardly and laterally projecting outlet nozzle between said base and said outer end, said spout being formed with an open inner end having a tapered container perforating terminal and a tubular venting element carried by the base and formed with an inner tapered container perforating terminal.
3. An attachable dispensing device for sealed containers including a base adapted to overlie an end of the container, a spring clip at one terminal of said base adapted to engage over a side of the container and a tubular pouring spout carried by and extending through the base, said spout being formed with a tapered container perforating terminal functioning to draw the spring clip into frictional engagement with the side of the container whereby to retain said device in applied position.
